Primary Examiner — Robert M Spear*Assistant Examiner* — Eliza Bennett-Hattan(74) *Attorney, Agent, or Firm* — Robert C. Montgomery;
Montgomery Patent & Design, LP(57) **CLAIM**

The ornamental design for a retractable electrical cord reel, as shown and described.

DESCRIPTION

FIG. 1 is a top perspective view of a retractable electrical cord reel with a switch knob portion in an up position;

FIG. 2 is a bottom perspective view of FIG. 1;

FIG. 3 is a top perspective view of the retractable electrical cord reel with a switch knob portion in down position;

FIG. 4 is a bottom perspective view of FIG. 3;

FIG. 5 is front view of FIG. 1;

FIG. 6 is a rear view of FIG. 1;

FIG. 7 is a left-hand side view of FIG. 1, wherein a right-hand side view is a mirror image of the left-hand side view;

FIG. 8 is a top view of FIG. 1; and,

FIG. 9 is a bottom view of FIG. 1.
